UNITED STATES PATENT OFFICE.

ANDREW E. MILLER, OF BALTIMORE, MARYLAND, ASSIGNOR TO SOLOMON HIMMEL, OF BALTIMORE, MARYLAND.

DISPLAY-RACK.

1,023,789.

Specification of Letters Patent.

Patented Apr. 16, 1912.

Application filed September 21, 1911. Serial No. 650,609.

To all whom it may concern:

Be it known that I, ANDREW E. MILLER, a subject of the King of Great Britain, residing at Baltimore city, State of Maryland, have invented new and useful Improvements in Display-Racks, of which the following is a specification.

This invention relates to certain new and useful improvements in display racks for 10 garments and the like.

In the present construction of the cases in which garment racks are usually retained, it is common to mount the doors which close the case so as to swing outwardly from the 15 latter. This usually requires considerable floor space and one of the objects of the present invention is to provide means for so mounting the doors as to effect an economy of such floor space. It is also frequently 20 the case that considerable space is available in the upper part of the case above the display rack.

A further object of the present invention is to utilize this space to receive the door 25 when the case is open.

The invention will be hereinafter fully set forth and particularly pointed out in the claims.

In the accompanying drawings: Figure 1 30 is a longitudinal sectional view of a display case, embodying my invention. Fig. 2 is a detail view illustrating a portion of the door mechanism. Fig. 3 is an enlarged transverse sectional view of one of the vertical guides, and its adjuncts.

Referring to the drawing, 10 designates a case of any suitable or preferred construction, the form illustrated comprising a base 11 provided with drawers, above which is 40 located the floor 12 of the display case. Located in said case is a display rack 13 of any suitable or preferred type adapted to be reciprocated back and forth in the case and to be rotated for the purpose of displaying 45 the garments supported thereby. At each end of the case near the top thereof is secured a track or guide 15, preferably a U-shaped angle iron and at the front of the case each of the tracks or guides is intersected by a similar guide 16 arranged vertically. Mounted in the guides 16 is a plunger 17 which is normally held in an upward position by a spring 18, the upward movement of said plunger being limited by 50 a stop 19. The door 20 is provided with

rollers 21, 22, the roller 21 being adapted to contact with the plunger 17. The spring 18 possesses sufficient power to counterbalance the weight of the door 20 when the latter is in the closed position. When it is desired 60 to open the door the same is swung forward from its lower edge, whereupon the rollers 22 will move backwardly in the guides 15 and the roller 21 and plungers 17 will move upwardly until said roller 21 is in alignment with the guide, at which time the overhanging portion of the door 20 will be supported by the spring 18 and said overhanging portion will act as a canopy to protect the garments when the rack 13 is in the 70 forward position. To close the door it is only necessary to reverse the foregoing operation. Mounted in opposite sides of the case 10 are levers 25, (but one lever being shown) the lower ends of which are connected with the carriage 26 of rack 13. The upper end of each lever is connected to the inner end of the door 20 by a link 27 provided with a slot 27' receiving a pin in door 20. By means of this arrangement, as the 80 door 20 reaches the rearward limit of its movement the carriage is caused to move forward; and when the carriage is returned the door is automatically moved forward to closing position. 85

Having thus explained the nature of my invention and described an operative manner of constructing and using the same, although without attempting to set forth all of the forms in which it may be made, or all 90 of the forms of its use, what I claim is:—

1. The combination with a case provided at each end with angular guides, a door provided with rollers adapted to engage said guides, and a spring pressed plunger mounted in one branch of each guide and adapted to engage said door. 95

2. The combination with a case, of horizontal guides at each end thereof, vertical guides intersecting the first mentioned 100 guides, a door provided with upper and lower rollers adapted to engage said guides, and counterbalancing means carried by the vertical guides and engaging the lower rollers for counterbalancing said door. 105

3. The combination with a case provided at each end with angular guides, a door provided with rollers adapted to engage said guides, a spring pressed plunger mounted in one branch of each guide and adapted 110

to engage said door, and stops for limiting the movement of said plungers.

4. The combination with a case, and a reciprocable garment supporting rack mounted therein, of intersecting horizontal and vertical guides carried by said case, a door constructed to engage said guides, and means actuated by the door for reciprocating said rack, said door actuated means being constructed to permit limited movement of the door along said horizontal guides before imparting movement to the rack.

5. The combination with a case, and a reciprocable garment supporting rack mount-

ed therein, of intersecting horizontal and vertical guides carried by said case, a door constructed to engage said guides, levers pivotally mounted in said case for reciprocating said rack, and slotted links connecting said levers with the upper end of said door, said links being approximately parallel with said horizontal guides.

In testimony whereof I have hereunto set my hand in presence of two subscribing witnesses.

ANDREW E. MILLER.
